UNITED STATES PATENT OFFICE.

JOSEPH E. PATTERSON, OF MARSHFIELD, WISCONSIN, ASSIGNOR OF TWO-THIRDS TO F. W. PATTERSON AND J. A. PETTET, OF UNITY, WISCONSIN.

WHIFFLETREE-HOOK.

SPECIFICATION forming part of Letters Patent No. 576,884, dated February 9, 1897.

Application filed August 18, 1896. Serial No. 603,146. (No model.)

To all whom it may concern:

Be it known that I, JOSEPH E. PATTERSON, a citizen of the United States, residing at Marshfield, in the county of Wood and State of Wisconsin, have invented a new and useful Whiffletree-Hook, of which the following is a specification.

The invention relates to improvements in whiffletree-hooks.

10 The object of the present invention is to improve the construction of whiffletree-hooks and to provide a simple, inexpensive, strong, and durable device for attaching traces to whiffletrees, adapted to enable the traces to 15 be readily connected to and detached from the whiffletree and capable of absolutely preventing them from becoming accidentally unfastened.

20 A further object of the invention is to provide a whiffletree-hook which will present no projections or points into which the driving reins can become caught.

25 The invention consists in the construction and novel combination and arrangement of parts hereinafter fully described, illustrated in the accompanying drawings, and pointed out in the claim hereto appended.

30 In the drawings, Figure 1 is a perspective view of a whiffletree-hook constructed in accordance with this invention. Fig. 2 is a plan view showing the same connected with a whiffletree. Fig. 3 is a detail perspective view of the whiffletree-hook, the separable hooks thereof being swung apart.

35 Like numerals of reference designate corresponding parts in all the figures of the drawings.

40 1 designates a whiffletree-eye formed integral with a band or ferrule 2, which is secured on the end of a singletree 3 in the usual manner. The singletree-ring is detachably connected with a trace-eye 4 by a whiffletree-hook 7, which is provided at one end with a continuous eye 8 to receive the whiffletree-ring 45 and at its other end with a split eye to receive the eye 4 of a trace.

45 The eye 4 of the trace may be of any desired construction and may consist of a link or a chain or the like, as will be readily understood.

The split eye of the whiffletree - hook is formed by a pair of hooks 10 and 11 reversely disposed, whereby when the hooks fit together, as illustrated in Figs. 1 and 2 of the accompanying drawings, one hook will close the 55 mouth or entrance of the other to form a continuous eye, and the strain on the whiffletree-hook will prevent the hooks 10 and 11 from becoming accidentally separated, whereby the eye of the trace or tug is securely confined 60 within the split eye of the whiffletree-hook. The hooks 10 and 11 have flat contiguous faces, and when they fit together the outer face of each is substantially flush with the adjacent face of the shank of the other. The 65 shanks of the hooks 10 and 11 are arranged substantially parallel, and the shank of the hook 10 has the eye 8 formed integral with it. The continuous eye 8, which is disposed in the same plane as the hooks 10 and 11, is provided with an extension or arm 12, arranged 70 parallel with the adjacent portion of the shank of the hook 10. The arm 12 and the adjacent portion of the shank of the hook 10 are squared or flattened, and the adjacent end of the shank 75 of the other hook is pivoted in the space between the arm 12 and the shank of the hook 10 by a transverse pin 13. The arm 12, by being spaced from the shank of the hooked end, provides an entrance-opening to the continuous eye 8, and when the shank of the hook 11 is pivoted in the space the entrance to the continuous eye 8 is closed to confine a whiffletree-eye therein. The inner end of the shank 80 of the hook 11 is flattened to conform to the configuration of the adjacent faces of the shank of the hook 10 and the arm 12. The short hook 11 is adapted to swing on the transverse pin or pivot 13 to separate the hooks to enable the trace-eye to be readily connected 85 to or detached from the singletree. 90

It will be seen that the whiffletree-hook is exceedingly simple and inexpensive in construction, that it will enable a trace or tug to be readily connected with and disconnected 95 from a whiffletree, and that it presents no projections or points into which the driving-reins can become caught.

It will also be apparent that the whiffletree-hook is adapted for all kinds of draft mech- 100

anism, and that traces and tugs cannot become detached by slackening them or turning short or the like.

What I claim is—

- 5 A whiffletree-hook comprising a shank having one end bent to form a hook 10 and having its other end bent to form a continuous eye 8 arranged in the same plane as the hook 10, the end of the shank which forms the eye 8 being extended along and spaced from the body portion of the shank to provide an entrance-opening to the continuous eye, and the hook 11 arranged contiguous to the hook 10
- 10

to form a split eye and having its shank pivoted in the space between the extension of the continuous eye and the shank of the hook 10, whereby the entrance to the continuous eye is closed to confine an eye or ring therein, substantially as described.

In testimony that I claim the foregoing as my own I have hereto affixed my signature in the presence of two witnesses.

JOSEPH E. PATTERSON.
